UNITED STATES PATENT OFFICE.

RALPH WALDO REQUA, OF CHICO, CALIFORNIA.

SQUARE.

1,139,229.

Specification of Letters Patent. Patented May 11, 1915.

Application filed August 5, 1914. Serial No. 855,112.

To all whom it may concern:

Be it known that I, RALPH W. REQUA, a citizen of the United States, residing at Chico, in the county of Butte and State of California, have invented certain new and useful Improvements in Squares; and I hereby declare that the following is a full, clear, and exact description thereof, reference being had to the accompanying drawings, which form part of this specification.

This invention is a novel drafting implement which I designate a "pocket square," and its primary object is to provide a square of simple construction which while possessing the usual functions of a square, has certain new and novel features capacitating it to perform new functions, and to accomplish work now performed by other devices.

A further object is to provide a square which may be conveniently carried in the pocket, and which will perform the work of the larger squares, by the simple process of marking off one side of the work, up to 6 inches in width, then transferring the square to the opposite side of the work.

I will explain the invention in detail and the mode of using same in connection with the accompanying drawings, in which—

Figure 1 is an obverse face view of the implement or square. Fig. 2 is an edge view thereof. Fig. 3 is a reverse face view thereof. Figs. 4 and 5 are enlarged detail sectional views showing the pivot pin.

As shown in the drawings the square comprises a flat substantially rectangular frame having vertical parallel side members 1 and 2; parallel top and bottom members 3 and 4 lying at right angles to members 1 and 2; and a diagonal member 5 which practically extends across the square from one top corner to the opposite lower corner thereof. The side members 1 and 2 are preferably extended beyond the outer edge of the member 4 as shown at 1^a, 2^a respectively. Said members are preferably formed integral, and may be of sheet metal or any other suitable material.

The outer edges of the members are preferably scaled as indicated in the drawings; the members 1 and 2 being preferably six inches in length measured from hole 6 outside; and the members 3 and 4 being preferably four inches in length inside. The member 1 is provided with a series of perforations 1^c a quarter of an inch apart, and with perforations 1^a alternating with the

perforations 1^c. The member 2 is provided with similar perforations 2^c a quarter of an inch apart.

In the member 1 about in line with the top or inner side of the member 4 is a pivot hole 6, and on the member 5 is a curved scale 6^a which has its axis at the point 6^p on the outer edge of member 1. The members 1, 5, 3 and 2 are scored with pitch lines 6^b 65 which radiate from the center 6^p.

To the rear face of the square is attached a flange 7, which may be formed of an L-shaped piece of metal fastened to the member 4, and projecting at right angles to members 1 and 2. This flange forms a guide by which the device can be used like an ordinary T-square. The ends of this flange 7 are flush with and at right angles to the side members 1 and 2 and are used as pivots and provide a means whereby the square may be rotated to the right or left to form the various angles or pitches which are scaled on the members 1, 5, 3 and 2 by the curved scale 6^a. On the reverse side of the square, (i. e. the side from which the flange 7 projects,) the members 1, 2 and 3 are preferably scaled as shown, and the member 5 on the reverse side may have an arc line 6^e struck from the center 6 and provided with 85 pitch lines 6^f which are numbered as shown.

Attached to the flange 7 adjacent pivot hole 6 is a pivot pin 8 which is adapted to be projected through hole 6 (see Fig. 4) and serve as a pivot for the square for a purpose 90 hereinafter described. The pin 8 is shown as attached to a head 8^a connected to bar 7 by a spring 8^c which spring normally tends to retract the pin (as shown in Fig. 5) so that it will not interfere with the free movement of the square over a surface when laid facewise thereupon; but when it is desired to pivot the square on the surface the pin 8 should be depressed, as indicated in Fig. 4, and its head 8^a engaged with a catch lug 7^a 100 on the flange 7, as shown in Fig. 4, thereby holding the pin in pivoting position.

The point of the pivot pin is normally retracted within the hole 6, but when the pin head is depressed the point of the pin is 105 projected through the hole into the surface beneath. The pin is held depressed or projected as long as the head engages catch 7^a. To release the pin a slight downward and side pressure permits the head to disengage 110 the catch, and resume its normal position as shown in Fig. 5.

- By marking or scoring the faces of the square as shown, any required pitch or angle or elevation as used in cutting rafters, or other building operations, can be obtained in three ways; the range of degrees being from 1 to 90. One way is to place the square face up on the surface to be marked; the guide flange 7 resting snugly against the side of the surface. Then draw a line along the outer edge of member 1, beginning at a point 6^p just opposite, and in line with the pivot 6 (Fig. 1) to the outer or upper end of member 1, then move the square with a circular motion, clockwise, using the end of the flange 7 (Fig. 2) as a pivot until the line 6^b marked with the desired pitch intersects the line on which the point 6^p rests, then draw a second line along the edge of member 1 from the pivot 6^p to outer end of square. This will give the desired pitch or angle, using the first line drawn as the base. A second way is to place the square on the surface as above described, then lay a straight edge of any kind on top of the square on the line 6^b of the angle or pitch desired and draw a line along the straight edge so placed. Another way is to place the square on the surface as above described and move it to the right, using the guide arm as a pivot as above described; then by counting the degrees backward, (or beginning at 90 and proceeding downward,) the desired pitch or angle may be obtained. The square also provides a simple and accurate means of drawing lines parallel with the length of the material to be marked or designed. The small holes 1^c, 1^d permit the "laying off" or drawing of lines $\frac{1}{8}$ inch apart by member 1.
- The single row of holes in member 2 is provided expressly for those mechanics or persons who are popularly called "left handed", and enables persons who use the left hand for marking or writing to use my square with equal facility.
- The square may be readily and easily held in one hand, which allows the free use of the other hand for marking and laying off the work. The parts 1^a, 2^a extending one inch below the member 4 permits the square to be balanced as described, as point 2^a extends underneath the lower side of the palm of the hand; while the member 1^a extends out over the forefinger, while the tips of the fingers are resting against the underside of the flange 7; therefore the points 1^a and 2^a prevent the hand from slipping in either direction along the member 4; the member 2^a lying underneath the hand acts as an extension to assist in carrying the weight of the main body of the square. The extensions also prevent any injury to the hand while moving the square backward or forward over the work, as anything interfering must necessarily engage the exten-

sion before reaching the hand. The extensions being scaled give two added inches in length when measuring any surfaces longitudinally.

By depressing the pivot pin 8 and inserting the point of any sharp instrument or pencil in any one of the holes 1^c, 1^d, 2^c and moving the square either to the right or left, a circular line is produced, which may be continued to produce a complete circle. The diameter of the circle may be varied at will by placing the marking instrument in the desired hole.

In squaring and longitudinally marking out with this square, the first end may be squared, the longitudinal line made, the length measured, and the last end squared without removing the square from the surface being so marked. Unusual accuracy in producing the longitudinal line is secured by the marking instrument being placed in the proper hole, while the guide arm being preferably six inches in length makes an even travel along the edge of the surface, and does not move in or out on passing over the usual close indentations on the edge of unsurfaced or unfinished materials or surfaces.

The invention further provides a 45 degree angle or $\frac{1}{2}$ pitch angle across the inside of the square by means of the member 5 which permits the marking of this angle from either side of the square. On the reverse side of the square and on the member 5 the lines 6^f are numbered from 4 to 12 along the edge of the arc 6^e. Between the Figs. 11 and 12 there is another line 6^h with a triangle mark at its top. The lines 6^f are used in making polygonal figures. The range being from four sides up to twelve. The line 6^h is used for laying off a figure with three sides.

To lay off an equilateral triangle draw a line along the edge of member 1 beginning at the point 6^p and ending at the upper or outer edge of the member. Next bring the point 6^p up to the end of the line just drawn and turn the square to the left or counterclockwise until the line 6^h intersects the first line drawn; then draw a second line from the point 6^p to the outer end as drawn in first line; next bring the point 6^p up to the end of the second line drawn, turn to the left as in second operation, bring the line 6^h down to intersection of second line, draw third line from 6^p to outer end, and the resulting figure will be an equilateral triangle.

Any polygonal figure may be drawn by using the square with the pivot pin depressed as in Fig. 3 also by use of the flange 7 as a guide line, and after the various sides have been drawn, and before the pivot pin has been released, or the square lifted from the work, a pencil or other sharp instru-

ment inserted in one of the most adjacent holes in the member 1 to one of the points of the figure, then rotating the square with a circular motion a circle will be produced 5 and if the length and angle of the various sides of the figure have been correctly made, each point of the figure will touch or be equidistant from the circle embracing the figure.

10 The foregoing explains some of the practical modes of using the square; other uses therefor will be readily understood by those familiar with such tools and the kind of work to be performed, and the square is not 15 limited to use in the specific operations above referred to.

What I claim is:

1. A square composed of parallel side members, two parallel top and bottom members connecting the side members, a diagonally arranged member connected with the other members, said side and end members being scaled on their edges and said diagonal member having scores adapted to indicate various angles relative to the edge of the bottom member, a guide flange attached to the reverse side of said square, and a pivot pin adjustably connected therewith.

2. An instrument for the purpose specified, comprising two parallel side members, two parallel top and bottom members at right angles to and connecting the side members, the ends of the side members extending 35 below the bottom member, said members being scaled on their outer faces and the side members being perforated, and a diagonally arranged member connected with the other members and scored to indicate 40 various angles relative to the edge of the bottom member.

3. A square composed of parallel side members, two parallel top and bottom members connecting the side members, a diagonally arranged member connected with the other members, said side and end members being scaled on their edges and said diagonal member having scores to indicate various pitches relative to the edge of the bottom member, a guide flange attached to the reverse side of said square, and a pivotal 50 pin connected with the square, substantially as set forth.

4. A square for the purpose specified, comprising parallel side members, top and bottom members connecting said members at right angles thereto, the side members extending below the bottom member, a diagonally arranged member connected at the opposite corners of the square, said side 55 members being provided with scales and perforations, and said diagonal member being provided with a protracting scale, and with scoring lines radiating from an opening in one of the side members, a guide 60 flange attached to the reverse side of said square, and a pivot pin adjustably connected therewith adjacent said opening.

5. A square for the purpose specified having four members forming a right-angled frame, each provided with a scale whereby measurements may be made on lines drawn along any or all of the four sides of such frame, a straight edged member extending diagonally across the frame at an angle of 70 forty-five degrees, each side member of the frame extending below the bottom member 75 thereof, substantially as specified.

6. A square for the purpose specified having four members forming a right-angled frame, each member being scaled, and an intermediate member extending diagonally across the frame at an angle of forty-five degrees; each side member extending below the bottom member of the frame and being 80 provided with perforations, and said diagonal member having scores to indicate various angles relative to the edge of the bottom member.

7. A square composed of parallel side members, two parallel top and bottom members connecting the side members, a diagonally arranged internal member connected with the other members and having scores to indicate various angles relative to the 90 edge of the bottom member, and a pivot attached to the square, substantially as set forth.

In testimony that I claim the foregoing as my own, I affix my signature in presence of 100 two witnesses.

RALPH WALDO REQUA.
